UNITED STATES PATENT OFFICE

JOHN CROOKSHANKS, OF GLASGOW, SCOTLAND

HEEL FOR FOOTWEAR

Application filed October 25, 1926, Serial No. 144,096, and in Great Britain December 1, 1925.

This invention relates to improvements in and connected with footwear, and refers to that class by which a worn part of the heel can be readily removed and a fresh wearing 5 piece inserted at any time as may be desired, and thereby avoiding the necessity of having so frequently to repair the heel.

In carrying out this invention, I provide a plate of steel, aluminum or other suitable 10 metal, having a short grooved-part at each side of the inner part thereof and with a ridge at the extreme inner end of the plate which connects the two grooved-parts together. I also provide a small ridge or clip 15 at the outer edge of the plate, holes being also provided for the attachment of the plate to the heel of the shoe.

I also provide a pad of rubber, leather or other suitable material with a groove of similar 20 dimensions to the grooved part formed on the plate so that, when the pad is placed in position, the grooves on each engage with each other and the small ridge engages with a recess on the outer end of heel, thereby locking 25 the plate and the pad together.

The plate may also be wholly or partially embedded in the heel and may also cover the whole heel or part only.

In order that this invention may be properly 30 understood and readily carried into effect, I have hereunto appended two sheets of drawings, of which

Figure 1 is a side view of the metal plate as applied to a gentleman's heel.

Figure 2 is a side view of the pad.

Figure 3 is an inverted plan of Figure 1.

Figure 4 is an end view of Figure 3.

Figure 5 is a plan of Figure 2.

Figure 6 is an end view of Figure 5.

Figure 7 is a side view of the heel of a lady's shoe, showing the pad in process of being inserted.

Figure 8 is a side view of the heel of a lady's shoe slightly different from that of Figure 7.

Figure 9 is an inverted plan of the metal plate shown in Figure 8.

Figure 10 is an end view of Figure 9.

Figure 11 is a side view of pad suitable for metal plate shown in Figures 8, 9 and 10.

Figure 12 is a plan of Figure 11.

Figure 13 is an end view of Figure 12.

Figure 14 is a side view of the heel of a lady's shoe of a slightly modified form to Figure 8.

Figure 15 is a side view of a flat heel of 55 a lady's shoe showing slightly different form of attachment.

Figure 16 is a sectional side view of a metal plate of slightly different form.

Figure 17 is a sectional view of the pad 60 in Figure 16.

Figure 18 is an inverted plan of Figure 16.

Figure 19 is a side view of a modified construction of metal plate as applied to a gentleman's heel, the pad being shown in act 65 of being inserted.

Figure 20 is a plan of Figure 19, the heel of the boot having been removed.

Figure 21 is an end view of Figure 19.

Figure 22 is a view of plate with what is 70 known as a horse-shoe clip catch.

Figure 23 is an end view of Figure 22.

Figure 24 is a sectional view showing a slightly modified form of ridge in plate.

Figures 25 and 26 are plan and side views 75 of single and double horse shoe clip.

Referring to Figures 1 to 6 of the drawings, A is the metal plate having the short grooved-part B on each side of the inner end of the plate B, formed by bending over the 80 sides of the plate and with a ridge C at the extreme inner end of the plate B connecting the two grooved parts together, or the plate B may be formed with the ridge C, as shown in Figure 24. At the outer end of the plate 85 B, there is a small ridge or catch D. E are suitable holes by which the plate is attached to the heel F of the shoe.

G is the pad of rubber, leather or other suitable material having a groove H equal 90 in dimension to that of the grooved part B in the plate A at the extreme inner end of the pad G. I is a recess on the inner end of the pad G for the reception of the ridge C on the plate A. J is a recess on the extreme 95 outer end of the pad for the engagement of the ridge D on the plate A. The pad G is inserted from the outer end of the heel towards the inner end and when in position becomes locked with the plate A against longitudinal 100

movement by the engagement of the ridges C and D with the recesses I and J, and against lateral movement by the grooves B and recesses H. When the pad is being inserted, it is sprung over the ridge D and when to be removed, the reverse action takes place. This construction admits of a cushion pad which is of substantially equal thickness throughout its length and width, and a pad 10 which not only is free to be compressed throughout its thickness toward the rear end of the heel, but which also presents the full thickness of the pad for wear at the back of the heel.

15 The pad G may also, if desired, be attached to the heel F by screws passing through the holes or openings K. A suitable screw or screws is or are provided for attachment of the pad to the heel of the boot or shoe.

20 Referring to Figures 7 and 15, the metal plate is embedded in the heel F and does not cover the whole surface of the heel, different forms of heel being shown.

25 Referring to Figures 8, 9, 10, 11, 12 and 13, the plate A is so formed that, when the pad G is inserted into position, the back portion of the plate A becomes embedded in the pad G through the recess L formed in the pad 30 and becomes locked in the manner hereinbefore described. In these figures no ridges are shown, although they can be applied, if desired.

35 Referring to Figure 14, the whole area of the heel F is covered by the plate A.

40 Referring to Figures 16, 17 and 18, the metal plate A is so pierced as to form on the opposite end a small projection M like a tooth on a rasp which, when the pad G is inserted, engages with a slot or slots N in the pad A, thereby preventing any back slip and thus effecting a better and more secure grip 45 of the pad G to the plate A. This may be applied to all the different forms described, if desired.

50 Referring to Figures 19, 20 and 21, the metal plate A is smaller in area than the base of the heel F and when in position no part of the plate A is exposed.

55 Referring to Figures 22, 23, 25 and 26 the ridge or clip D on the extreme outer end of the plate A is of horse-shoe clip formation and engages with the recess J in the pad G. The clip D is bent over into U-shaped form and when the plate A is placed in position, this U-part engages, as stated, with the recess J in the pads. A double U-part may be used to effect a better hold.

60 It is to be understood where parts are referred to in some of the figures and not in others, such as the clips or ridges for effecting greater security of attachment of the pad to the plate these are equally applicable to all forms of heels, both ladies' and gentle-65 men's.

Having now particularly described and ascertained the nature of the said invention and in what manner the same is to be performed, I declare that what I claim is:

A detachable heel comprising a fixed plate 70 for permanent attachment to the bottom of a heel and having at its forward corner portions depending inturned flanges disposed substantially in parallel relation to each other and extending rearwardly not more than half the length of the plate, and a pad 75 adapted to be detachably mounted on the plate and having grooves in its opposite sides and at its forward corner portions opening through the forward end of the pad to receive the flanges of the plate by a forward sliding movement of the pad, said grooves being substantially the length of the flanges to provide stop shoulders on the pad limiting the forward sliding movement thereof and 80 leaving the rear portion of the pad intact, and means for holding the pad from sliding backwardly when in place.

In witness whereof I affix my signature.

JOHN CROOKSHANKS.
